UNITED STATES PATENT OFFICE.

SABBATIA CHAIT, OF NEW YORK, N. Y., ASSIGNOR TO MAXWELL MOTOR CORPORATION, OF HIGHLAND PARK, MICHIGAN, A CORPORATION OF WEST VIRGINIA.

DESIGN FOR AN ORNAMENT FOR AUTOMOBILE RADIATOR CAPS.

Application filed March 23, 1925. Serial No. 12,818. Term of patent 14 years.

To all whom it may concern:

Be it known that I, SABBATIA CHAIT, a citizen of the United States, residing at New York, in the county of New York and State of New York, have invented a new, original, and ornamental Design for an Ornament for Automobile Radiator Caps, of which the following is a specification, reference being had to the accompanying drawing, forming a part thereof, in which: The figure is a front elevation showing my design. What I claim is: The ornamental design of an ornament for automobile radiator caps, as shown. SABBATIA CHAIT.
